US0D1030668S

(12) **United States Design Patent** (10) **Patent No.:** **US D1,030,668 S**
(45) **Date of Patent:** **** Jun. 11, 2024**

(54) **ELECTRIC MOTOR**

(71) Applicant: **Meritor Electric Vehicles Germany GmbH**, Nuremberg (DE)

(72) Inventors: **Cheng Shuai Lu**, NanYang (CN); **Han Wang Zhao**, Tianjin (CN); **Hai Bin Li**, Tianjin (CN); **Hui Lai Liu**, Shenzhen (CN)

(73) Assignee: **Meritor Electric Vehicles Germany GmbH**, Nuremberg (DE)

(**) Term: **15 Years**

(21) Appl. No.: **29/843,857**

(22) Filed: **Jun. 24, 2022**

(30) **Foreign Application Priority Data**

Dec. 27, 2021 (CN) 202130862001.8

(57) **CLAIM**

The ornamental design for an electric motor, as shown and described.

DESCRIPTION

FIG. 1 is a front elevational view of an electric motor showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and left-side perspective view thereof; and,

FIG. 8 is a rear, bottom and right-side perspective view thereof.

1 Claim, 8 Drawing Sheets
